UNITED STATES PATENT OFFICE.

CHARLES P. BLEY, OF CEDARFALLS, IOWA.

BOOK-SUPPORT.

SPECIFICATION forming part of Letters Patent No. 734,218, dated July 21, 1903.

Application filed February 14, 1903. Serial No. 143,358. (No model.)

To all whom it may concern:

Be it known that I, CHARLES P. BLEY, a citizen of the United States, residing at Cedarfalls, in the county of Blackhawk and State 5 of Iowa, have invented a new and useful Book-Support, of which the following is a specification.

This invention relates to desk or book-support attachments to chairs and similar articles of furniture, and has for its object to simplify and improve the construction of devices of this character and to increase their usefulness; and the invention consists in certain novel features of the construction, as 15 hereinafter shown and described, and specified in the claim.

In the drawings illustrative of the invention, in which corresponding parts are designated by like denoting characters, Figure 1 20 is a perspective view of the device applied to a chair with the parts distended. Fig. 2 is a reversed perspective view of the table portion. Fig. 3 is a cross-sectional view of the table portion with the section folded.

25 The improved device consists of a table portion composed of two sections 10 11, divided longitudinally and of unequal lengths and flexibly united, as by hinges 12 13, so that the parts are foldable, as shown in Fig. 30 3. The two parts 10 11 are provided, respectively, with cleats 14 15, arranged with their adjacent ends abutting, as shown in Fig. 2, to receive the strains and relieve the hinges to a large extent, the cleats at the same time 35 forming transverse supports to the sections 10 and 11. The hinges 12 13 are arranged upon the upper sides of the sections 10 11, and the section 11 is provided with a book-rest in the form of a stop or cleat 16, as shown 40 in Fig. 1, which becomes a parting-block to hold the sections 10 11 in parallel relations when folded, as in Fig. 3, to form a space between the two sections.

Beneath the section 10 is attached a socket- 45 clip 17, provided with a transverse aperture, in which the horizontal arm of a bent standard 18 fits and secured in place by a set-screw 19, as shown. The vertical arm of the standard is adjustably connected by a clamp 20 to 50 the chair 21 or other support, the clamp having a set-screw 22, engaging the chair, and a

similar set-screw 23, engaging the standard. By these connecting means it is evident the table portion may be adjusted longitudinally or rotatively upon the standard, as may be required, and likewise adjusted vertically relative to the chair or swung around horizontally. The table portion 10 11 may thus be adjusted to any desired angle or "set" in any desired position relative to the chair or other support. The shorter section 11 thus extends in front of the person occupying the chair and provides a support for books or writing material, while the longer section 10, coming more to one side, serves as an arm-rest. 65 The shorter section may be folded over upon the longer section to permit easy ingress or egress to the chair.

It will be noted that the occupant of the chair may push his book or writing material 70 from the section 11 onto the section 10 and then by folding the section 11 over onto the section 10 the article will be confined within the space formed between the two members and will always be handy when the occupant 75 resumes his seat again, the stop 16 causing such a space to be formed by supporting the section 11 above the section 10 and parallel thereto.

A pen or pencil clip may be attached, if required, as shown.

If required, the device may be employed for supporting articles contiguous to a bed or couch by adjusting the table to a level position and reversing the position of the standard 85 18. By this means the device may be employed as an invalid's table without altering or detaching any of the parts.

The lower chair-gripping jaws of the clamp will have sufficient range to adapt them to 90 any size of chair or other structure to which it is to be attached, and the parts which engage the chair will be provided with felt or other suitable protecting means to prevent abrasion.

The parts may be of any size and any required material and may be ornamented or "finished" in any desired manner and adapted to any style of chair or other piece of furniture.

The device may be attached to any desired part of the chair—either the body, arms, or

other part—or to any style of chair, and will be found very convenient for the purposes described.

The device when not required may be folded into small space for storage or transportation.

Having thus described the invention, what I claim is—

A book-support comprising two longitudinally-hinged sections, one of said sections terminating short of the end of the other section, a transverse stop secured across the upper face of the shorter section, said shorter section being adapted to be folded upon the

longer section to cause the stop to rest upon the upper face thereof for supporting the shorter section above the same and parallel thereto, to form a space between the two sections for the reception of an article, and means for adjustably supporting the two sections.

In testimony that I claim the foregoing as my own I have hereto affixed my signature in the presence of two witnesses.

CHARLES P. BLEY.
